WOOD BENDING APPARATUS

Oliver G. Catron, Barbourville, Ky.

Application January 24, 1944, Serial No. 519,519

4 Claims. (Cl. 144—266)

The present invention relates broadly to a simple and inexpensive apparatus for bending wood, but more specifically is intended for use in the expeditious manufacture of canes, umbrella shafts and the like.

In the manufacture of canes the wooden rods are first softened by steam or water and then bent to the desired form and placed in drying kilns for several hours at least. Inasmuch as many canes may be bent in a few hours, even manually by a single workman, it becomes highly essential that the parts which secure the bent rods while in the kiln be few in number and of low cost. It is also of paramount importance that the apparatus be of simple construction so as to facilitate easy operation to the end that a maximum number of rods be bent per unit of time.

It is an object of the present invention therefore to provide a wood bending apparatus of relatively few and inexpensive parts which are of simple design and readily operated at high speed.

Another object of the invention resides in the provision of a wood bending apparatus in which the parts which remain with the bent strip when it is placed in the drying kiln are reduced to a minimum.

A further object of the invention resides in the provision of means to maintain the shaft of the cane or the like in its original straight condition during the bending operation in which the handle is formed.

Other objects and advantages of the invention will be apparent from the following description when taken in connection with the accompanying drawing, in which,

Figure 1 is a plan view of the novel bending apparatus in use, parts being broken away.

Figure 2 is a fragmentary view of the apparatus showing the cane bent to form the handle, but before being removed from the head.

Figure 3 is a view similar to Figure 2 showing the assembly ready to be placed in the drying kiln.

Figure 4 is a perspective view of a clamp for holding the parts in their bent formation.

Figures 5 and 6 are detail sectional views taken on lines 5—5 and 6—6 respectively of Figure 1.

Figure 7 is a sectional view taken on line 7—7 of Figure 1, and

Figure 8 is a fragmentary perspective view of a bendable strip of metal and an abutment, which form a backing for the cane to secure a uniform bend and a straight body portion.

Referring to the drawing in greater detail, the numeral 1 indicates a portion of a bench or the like on which the bending apparatus may be

mounted for manipulation by the operator. The head or base 2, which may be formed of cast metal or the like, may be fixedly secured to the bench 1 by means of a center bolt 3 and an offset pin 4.

5 A circular boss 5 forms an integral part of the head and is provided with a horizontal flange 6 at its lower edge which forms a guide and support for the cane as it is being bent to form a handle. Loosely surrounding the boss 5 and 10 separable therefrom is a metal ring 7 preferably provided with an external groove 8 to form a seat for the handle of the cane.

The head 2 is also provided with a radial extension 9. This portion of the apparatus is 15 formed with a slot 10 in its upper surface which extends substantially tangentially of ring 7 and the boss 5 on which the ring is mounted. A slit 11 is also formed in a wall of the extension 9 and communicates with the slot 10. The extension 9 is also provided with an abutment or shoulder 12; these several parts 10, 11 and 12 being adapted to removably hold and support a strap-metal bending element 13.

20 A pin 14 is secured in one end of strap 13 and is adapted to engage the outer wall of the member 9 when the strap is passed downwardly into the slit 11. A block or abutment 15, preferably of metal, is secured to strap 13 by a rivet 15' and is adapted to engage the shoulder 12 on extension 9 when the strap is applied to the head.

The remote end of strap 13 may be provided with an aperture 16 adapted to detachably engage a pin 17 extending laterally of a metal sleeve or tube 18, adjacent the end thereof. A ring 19 35 slidably mounted on the tube 18 may be employed to overlap the end of strap 13 as indicated in Figure 1, although this element of the apparatus is not essential. Detachably connected to the opposite end of the tube 18, as by means of a threaded ring 20, is a tube 21 of slightly smaller internal diameter. The tube 21 is internally threaded to receive a threaded bolt 22 provided with an operating handle 23. This construction provides for operation upon sticks of different length as well as tapered sticks. But it is to be particularly noted that by the rotation of the member 22 the far end of the wooden stick will be forced tightly against the abutment 15, so that both ends of the stick are firmly held, and thus lengthening of the stick during the bending operation is prevented.

And it is also to be noted that the diameter of the tube 21 is such that the end 40 of the stick fits snugly therein, and thus the end 50 is encompassed and firmly held, so that crack- 55

ing does not occur when pressure is exerted on the end by the threaded bolt 22.

The wooden stick or the like which is to be bent to provide a curved handle and a straight body portion, such as an ordinary cane, is indicated by numeral 24, and numeral 25 indicates a U-shaped clamp for holding the parts in bent condition when removed from the head 2 and while being processed in the drying kiln.

In the operation of the apparatus, the strap 13 is positioned in the slot 10 as indicated in Figure 1. The wooden rod 24, of proper length and suitably steamed or otherwise treated along the portion to be bent, is then assembled with the tube 18, and the pin 17 inserted in the aperture 16 of strap 13. It will be noted that the wooden rod is in alignment with block 15, and the bolt 22 is now screwed into the tube 21 so as to force the opposite end of the rod into firm contact with block 15. The ring 19 may be moved into the position shown in Figure 1, and the operator then produces the curve in the handle (Figure 2) by swinging the sleeve 18 and related parts about the ring 7 as a center. In this operation the strap 13 serves to force and maintain the rod into close contact with the ring 7, thereby producing a uniform bend in the handle portion of the cane, while the tube or sleeve 18-21 serves to hold the body portion of the cane substantially straight. In this operation also the flange 6 on the head 2 serves as a guide in directing the bent portion of the rod into engagement with the groove 8 on ring 7.

After this operation is completed the U-shaped clamp 25 is applied, as indicated in Figure 2, to hold the parts in their bent condition; one leg of the clamp being placed against the head of rivet 15' to prevent accidental movement of the clamp.

The formed cane is now ready for processing in a drying kiln, and to this end the assembly shown in Figure 3, namely, the ring 7, bent strap 13 with block 15, clamp 25 and cane 24, is removed from the head 2 and placed in the kiln. The operator then applies another ring 7 and strap 13 to the head 2, and another rod is inserted and bent to shape, etc. It is to be particularly noted that the only parts placed in the kiln, aside from the cane itself, are a ring 7, strap 13 and clamp 25. These parts are very simple and inexpensive and it is obvious that a great many duplicates may be provided, without undue cost, so that the operations may be continued until the finished canes are taken from the kiln and the rings, etc., removed and again placed in association with the head 2.

Should it be desired to bend rods of a different length from that indicated it is only necessary to disconnect the tubes 18 and 21 and substitute a different length tube 18 or 21 to provide the required length of tubing necessary to bring the rods into firm engagement with the block 15.

It should also be noted that if the apparatus is to be power driven rather than manually operated, the head 2 would be partly rotated to pro-

vide the bend rather than by swinging the tube 18-21 and related parts.

From the foregoing description taken in connection with the accompanying drawing, it will be apparent to those skilled in the art that I have provided an exceedingly simple and inexpensive apparatus for bending wood to produce canes and the like, that the parts are relatively few and of simple design, that the structure is such as to permit of expeditious operation while producing a uniform bend and maintaining the body of the rod in its original straight condition, and that the parts which remain with the rod while in the drying kiln are relatively few and of inexpensive construction.

In accordance with the patent statutes I have described what I now believe to be the preferred construction of the apparatus, but it is to be understood that various changes may be made in the structural details without departing from the spirit of the invention, and it is intended that all such changes be included within the scope of the appended claims.

What is claimed is:

- 25 1. Wood bending apparatus comprising a base member, a ring loosely mounted thereon, a flexible band connected with the base member and cooperating with the ring for bending a wooden rod about the ring, and a tube detachably connected to the band for operating the same and for receiving and maintaining certain parts of the wooden rod in its original condition.
- 30 2. Wood bending apparatus comprising a base member, a ring removably mounted thereon, a flexible band connected with the base member and cooperating with the ring for bending a wooden rod about the ring, an abutment on the band adjacent the ring, a tube detachably connected to the band, and means associated with the tube for forcing the material to be bent into firm contact with the abutment.
- 35 3. Wood bending apparatus comprising a base member, a ring loosely mounted thereon, a flexible band connected with the base member and cooperating with the ring for bending a wooden rod about the ring, an abutment on the band adjacent the ring, a tube associated with the band, said tube being of a diameter to snugly fit about one end of the wooden rod to be bent, and a threaded bolt mounted in the tube to force the other end of the wooden rod against said abutment.
- 40 4. Wood bending apparatus comprising a base member, a ring loosely mounted thereon, a fixed shoulder carried by the base member, a flexible metal band for bending a wooden rod about the ring, means adjacent one end of the band for removably connecting the band with the base member, an abutment on the band adjacent the ring, one side of said abutment engaging said shoulder on the base member, and means connected with the other end of said band for forcing the wooden rod against the abutment, said means including a threaded bolt.

OLIVER G. CATRON.
